UNITED STATES PATENT OFFICE.

HARRY PENDLETON, OF COLUMBUS, OHIO.

LIFTING-JACK.

1,118,949.

Specification of Letters Patent.

Patented Dec. 1, 1914.

Application filed May 11, 1914. Serial No. 837,735.

To all whom it may concern:

Be it known that I, HARRY PENDLETON, a citizen of the United States of America, residing at Columbus, in the county of Franklin and State of Ohio, have invented certain new and useful Improvements in Lifting-Jacks, of which the following is a specification.

The present invention relates to improvements in lifting jacks, and is designed particularly for the purpose of providing a device of this character comprising comparatively few parts, which is simple in construction and operation, facile in its manipulation and efficient in performing the functions for which it is intended.

The primary object of the invention is the provision of a mechanically and manually operated lifting jack of the "step by step" type embodying among its comparatively few elements, an operating lever, which may be detached or applied quickly and with facility, and which is readily removable so that it may be compactly stored with the other parts of the jack for convenience in transportation as well as for storage.

The invention consists essentially in the combination with a specially constructed pedestal of a novel form of relatively movable post and peculiarly constructed operating lever which is readily detachable, and in other combinations and arrangements of parts as will hereinafter more fully appear.

In the accompanying drawings I have illustrated one complete example of the physical embodiment of my invention constructed according to the best mode I have so far devised for the practical application of the principles of the invention.

In the drawings: Figure 1 is a side elevation of the lifting jack showing the holding detent in operative position. Fig. 2 is an edge view of the jack as seen from the right in Fig. 1, the operating lever being omitted for convenience of illustration. Fig. 3 is a sectional plan view on line 3-3 of Fig. 2. Fig. 4 is a view of the top part of the lifting jack, similar to Fig. 1, but in the present figure the detent is inoperative and the lever is lifting the slidable post. Fig. 5 is a top plan view of the operating lever, detached from the jack.

There are three essentially elemental features to the lifting jack viz: the standard

or pedestal 1; the slidable post 2 and the operating lever 3. These three devices are separable from each other, but they co-act when in operative position to perform their distinct functions. The pedestal, as are also the other parts of the lifting jack, is of suitable metal, is hollow, and has its sides slotted as at 4, 4. The slots extend from the base 5 up to the top of the pedestal which is crowned by a cap piece 6 which is open or hollow, but the slots 4 in the pedestal are closed by the outwardly extending wings 7, 7. Thus it will be understood that the hollow and slotted pedestal is crowned by a cap piece which extends integrally around the top of the pedestal. Located just below the cap piece 6 and projecting from one side of the pedestal is a lug 8 fashioned with a pair of laterally projecting bosses 9, 9 which are adapted for use as the fulcrum of the operating lever. The pedestal and its component parts are formed integral and the opening through the pedestal may extend from end to end thereof.

The slidable post 2 is preferably rectangular in cross section to fit neatly within the hollow pedestal, and it will readily be understood that the post is designed to be moved relatively to the pedestal. The post is formed with a series of laterally projecting integral studs 10, 10, at each side thereof, and spaced at regular intervals from the top to the bottom, and the top of the post is crowned by a supporting block 11 as usual.

The operating lever 3 is fashioned with a handle 12 at one end, and at its opposite end is bifurcated or forked as at 13. A complementarily forked detent 14 is pivoted to the lever above its forked end, by the pivoted side links 15, and an integral arm 16 of the detent is pivoted at 17 to a slide strap 18 which has a pair of sleeves 19 embracing the lever 3 so that the strap is free to slide on the lever.

The operation of the lifting jack will be apparent from an inspection of the drawings, and a brief description will suffice for a clear understanding of the manipulation of the device. The operating lever is manipulated in manner similar to a crow-bar with the lever resting on the bosses 9 as a fulcrum, and the short end of the lever, or the bifurcated end which straddles the pedestal is adapted to engage under the oppo-

sitely arranged pairs or studs to lift the post when the handle end is turned down as in Fig. 4. When the handle end of the lever is lifted up the short arm of the lever is withdrawn from the studs, but the pivoted 5 detent is, by the same motion, pushed in under a pair of studs and caused to slide across the top of and in contact with the cap piece 6 of the pedestal. The continued up and down movement of the lever on its 10 fulcrum will alternately lift and hold the post as will be readily seen, the operating lever being a rigid bar, and the pivoted detent being free to move in and out of position between the studs and the top of the 15 cap piece. When it is desired to lower the jack from raised position, the lever is turned down and at the same time slightly withdrawn in order that the short arm of the 20 lever may escape the studs above it and also to permit the detent to be withdrawn from under the studs which are resting upon it. In this manner the post is lowered "step by 25 step" and the detent acts as an escapement just as before described in lifting the post. The operating lever is separate from and may be readily disassociated from the jack when not being used and may be snugly packed away for storage.

30 From the above description taken in connection with my drawings it is evident that I have produced a lifting jack which performs the functions and fulfills the purposes set forth as the object of the invention.

Having thus fully described my invention, 35 what I claim is:—

1. The combination in a lifting jack with a hollow, slotted pedestal having a fulcrum member thereon, of a post slideable in the pedestal and formed with spaced members 40 thereon projecting through the slotted pedestal, and an operating lever provided with a holding detent for imparting a step by step lifting motion to the post.

2. The combination with a hollow, slotted 45 pedestal and a post slideable therein formed with a series of spaced studs projecting through the slotted pedestal, of an operating lever fulcrumed on the pedestal to engage said studs, and a detent pivoted on said lever to co-act therewith in moving the post relative to the pedestal.

3. The combination with a hollow, slotted 55 pedestal formed with a cap piece and a post slideable in the pedestal having spaced studs projecting through at opposite sides of the slotted pedestal, of an operating lever fulcrumed on the pedestal and formed with a bifurcated short arm engaging said studs, and a complementary detent pivoted on the 60 lever co-acting with said studs and said cap piece as described.

In testimony whereof I affix my signature in presence of two witnesses.

HARRY PENDLETON.
